CLAIM

The ornamental design for a truck bed tonneau, as shown and described.

DESCRIPTION

FIG. 1 is a perspective view of a truck bed tonneau made according to the present invention;

FIG. 2 is a side elevation view thereof;

FIG. 3 is an end elevation view thereof;

FIG. 4 is a bottom plan view thereof; and,

FIG. 5 is a top plan view thereof.

In the drawings, the broken lines depict a truck and form no part of the claimed design.
